DESIGN FOR A DECORATIVE SHEET OF METAL FOIL

Charles S. Price, Hollis, N. Y.

Application May 8, 1937, Serial No. 69,225

Term of patent 14 years

To all whom it may concern:

Be it known that I, Charles S. Price, a citizen of the United States, residing at Hollis, in the county of Queens, Long Island, and State of New York, have invented a new, original, and ornamental Design for a Decorative Sheet of Metal Foil, of which the following is a specification, reference being had to the accompanying drawing, forming part thereof.

Fig. 1 is a face view of a decorative sheet of metal foil, slightly enlarged, showing my design; and

Fig. 2 is an enlarged sectional view of the sheet taken on the line II—II of Fig. 1.

The drawing is lined to indicate color contrasts as shown.

The design consists of a series of closely spaced, interlocking stars, characterized by edge embossment, and of a color the same as or contrasting with that of the background.

I claim:

The ornamental design for a decorative sheet of metal foil as shown and described.

CHARLES S. PRICE.
